UNITED STATES PATENT OFFICE.

BENJAMIN F. NUTTING, OF WATERTOWN, MASSACHUSETTS.

IMPROVEMENT IN COPY-HOLDERS.

Specification forming part of Letters Patent No. **155,202**, dated September 22, 1874; application filed July 23, 1874.

To all whom it may concern:

Be it known that I, BENJAMIN F. NUTTING, of the city of Watertown and State of Massachusetts, have invented certain Improvements in Adjustable and Portable Copy-Holders, of which the following is a specification:

The nature and objects of the invention relate to a portable and adjustable copy-holder; and it consists in the construction, arrangement, and susceptibility of adaptation, which will be hereinafter described.

In the accompanying drawings, which form a part of this specification, Figure 1 is a longitudinal sectional view illustrating my invention, and Fig. 2 a plan view of the same.

Referring to the drawings, A represents the clamp-plate, which is adapted to be attached to a table or other article of furniture, let the position of the same be vertical, horizontal, or otherwise. It is made fast and secured by means of set-screw *a*, which carries on its inner end a bearing-plate, *a'*. The body of this plate is made and formed so as to correspond with a disk, *B*, on the standard *B'*, and it acts in connection therewith, being susceptible of being turned to any angle desired, and secured thereby by means of set-screw *b*. On the opposite end of this standard *B'* is another disk, *C*, arranged at right angles with the body of the clamp-plate *A*, and operating against this disk is another, *C'*, which is attached to the standard *D*. *D* is a standard, being provided at one end with the disk *C'*, rigidly attached thereto, and at the other with the paper-clip *E*. This clip is of the ordinary

form and construction, except as to the means, *e*, for clamping the same to the standard *D*, which, being capable of being turned on the standard as desired, is considered novel.

These clamping-arms *e* are constructed and adapted to clasp the standard *D*, and allow the clip *E* to be revolved around the same at will, and also to be adjusted vertically, as is obvious.

The disks *C'* and *B C* and body of clamp-plate *A*, being arranged at right angles to each other, allow of a multitudinous variety of directions in which the copy or paper may be held, and the spring paper-clip, being susceptible of being turned as desired on the standard *D*, multiplies the same still further. The operator, by this arrangement, may readily adjust his manuscript or paper, with reference to light, &c., to suit himself.

I claim—

1. The spring-clip *E*, provided with clamping-arms *e*, in combination with the standard *D*, as shown and specified.

2. The clamp-plate *A*, adjustable disk *B*, and standard *B'*, in combination with the disks *C C'*, and set-screw and standard *D*, substantially as and for the purposes set forth.

In testimony that I claim the above I have hereunto subscribed my name in the presence of two witnesses.

BENJ. F. NUTTING.
